EDWARD B. NOWOSIELSKI, OF BLOOMFIELD, NEW JERSEY, ASSIGNOR TO SPLITDORF
ELECTRICAL COMPANY, OF NEWARK, NEW JERSEY

RATCHET WRENCH

Application filed September 9, 1926. Serial No. 134,366.

This invention relates to improvements in ratchet wrenches, and is especially adapted for the heaviest or hardest kind of service to which a wrench of this character may be put, and therefore the principal object of my invention is to provide a ratchet wrench, which will stand hard usage, yet one that is relatively simple in its construction and not expensive to manufacture.

10 My invention will best be understood by reference to the attached drawing wherein:

Figure 1, is a plan view of the complete ratchet device.

Figure 2, is a side view of Figure 1.

15. Figure 3, is a part vertical section through the device, Figure 4 is similar to Figure 3 but showing

Figure 4, is similar to Figure 3 but showing a different form of holding and positioning means, while

20 Figure 5, is a further modified form of the holding and positioning means.

In the different views wherein like numbers refer to the same parts, 1 is the body portion of a ratchet wrench having an integral shank 2, all preferably made as a drop forging; the body portion 1, is preferably cylindrical in shape up to the point where it terminates in the shank. The body portion 1, preferably has a pair of flat substantially parallel sides 3 and 4, which may be, as illustrated, somewhat less in thickness than the diameter of the shank 2. The body

portion 1, has a circular hole bounded by the line 5, passing through from the face 3, to the face 4. Adjacent to the hole 5, and preferably centrally disposed between the faces 3 and 4, is an annular groove 6. In the body 1, extending from the hole 5, toward the shank 2, is a slot 7 and positioned in the slot

40 7, is a pawl 8, held in position by a plunger 9, having an end 10, which enters a hole in the pawl 8. The plunger 9 is presumably held against the pawl by a spring 11, the tension of which may be adjusted by a screw 12, 45 which is threaded into a bore in the shank 2.

The outer portion of this bore in the shank 2, represented by the dotted line 13, Figure 1, is adapted to receive a lever for operating the ratchet device.

50 Rotatably positioned within the hole 5, is

a ratchet wheel 14, which is in thickness substantially the same as the distance between the faces 3 and 4, so that the ratchet wheel is practically flush with these faces, when in operative position. The overall diameter of the ratchet wheel 14, is such that there is an operating clearance between the teeth and the edge of the hole 5, whereby some support for the ratchet wheel 14, may be obtained from the body 1. The wheel 14, has an annular groove 15, positioned, so as to cooperate with the groove 6, in the body 1, and positioned within the two grooves 6 and 15, is a suitable number of rotatable or movable members 16. In the form shown in Figure 3, these rotatable members 16, are in the shape of cylindrical rollers, which are preferably of hard material, or having hardened surfaces. In the form shown in Figure 4, the rotatable members 16 are shown as balls. In either case these rotatable members will feed into the grooves 6 and 15 through the medium of the slot 7, before the pawl 8, is put into position. Particular attention is directed to the pawl 8, which has a plurality of teeth adapted to fit the teeth in the ratchet wheel 14. In the ordinary ratchet wrenches, only one tooth is used in the pawl, but by using two for example, the strength at this point is increased four times, the strength being increased as the square of the number of teeth on the pawl. 55 60 65 70 75 80

It will be observed that with respect to Figures 1, 2, 3, and 4, that the body and shank portions of the ratchet are integral devices, and that the only screw used in the whole arrangement is one which is designated by the number 12, and adjustably holding the pawl 8 in position. 85

While I prefer either of the arrangements shown in Figures 3 and 4 for supporting and positioning the ratchet member 14, it is to be understood that the ratchet wheel may be held in place by other means such as a suitable number of positioning members, as illustrated by the screws 17 in Figure 5, which has an end 18 fitting within the groove in the ratchet wheel. It may be noted that the ratchet wheel 14, is preferably provided with a polygonally shaped hole to receive the end 100

of a socket wrench, it being understood that various sizes of socket members may be used, all having a shank to fit the hole 19, whereby the ratchet device will operate various sizes of socket wrenches.

Other details may also be varied without departing from the spirit of my invention and the scope of the appended claims.

Having thus described my invention, what I claim is:

1. In a device of the class described, a body portion having a shank, said body portion having a circular hole therethrough and an annular groove opening into said hole, a ratchet wheel to fit within said hole, said ratchet wheel having means for attaching a wrench and having an annular groove in alignment with the groove in said body portion, means fitting within both said grooves to hold and assist in positioning the ratchet wheel in operative position, said body portion having a slot extending from the edge of the hole toward the shank, a pawl positioned in said slot, said pawl having a groove therein to pass said holding and positioning means and means carried within the shank to resiliently hold the pawl in engagement with the ratchet wheel.

2. In a device of the class described, a body portion having a shank, said body portion having a circular hole therethrough and an annular groove opening into said hole, a ratchet wheel to fit within said hole, said ratchet wheel having means for attaching a wrench and having an annular groove in alignment with the groove in said body portion, anti-friction devices fitting within both said grooves to hold and assist in positioning the ratchet wheel in operative position, said body portion having a slot extending from the edge of the hole toward the shank a pawl positioned in said slot, said pawl having a groove therein to pass said anti-friction devices as the body turns with respect to the ratchet wheel, a spring pressed plunger carried by the shank for holding the pawl in engagement with the ratchet wheel and adjustable means for holding the spring and plunger in position.

3. In a device of the class described, a body portion having a shank, said body portion having a circular hole therethrough and an annular groove opening into said hole, a ratchet wheel to fit within said hole, said ratchet wheel having means for attaching a wrench and having a double row of teeth spaced by a groove so disposed as to be in alignment with the groove in said body portion when the ratchet wheel is in working position in said hole, rotatable devices loosely positioned in both of said grooves to hold and assist in positioning the ratchet wheel in operative position, said body portion having a slot extending from the edge of the hole toward the shank, a pawl positioned in said slot,

said pawl having a groove therein to pass said rotatable devices as the body turns with respect to the ratchet wheel, a spring pressed plunger carried by the shank for holding the pawl in engagement with the ratchet wheel and adjustable means for holding the spring and plunger in position.

4. In a device of the class described, a body portion having a shank, said body portion having a circular hole therethrough and an annular groove opening into said hole, a ratchet wheel to fit within said hole, said ratchet wheel having means for attaching a wrench and having an annular groove in alignment with the groove in said body portion, means fitting within both said grooves to hold and assist in position the ratchet wheel in operative position, said body portion having a slot extending from the edge of the hole toward the shank, a pawl positioned in said slot, said pawl having a groove therein to pass said holding and positioning means and means carried within the shank to resiliently hold the pawl in engagement with the ratchet wheel, said pawl having a plurality of teeth for simultaneously engaging a plurality of teeth on the ratchet wheel.

5. A ratchet wrench comprising a one piece body having an integral shank, said body having a hole therethrough, and an annular groove adjacent the hole and the shank having a bore extending through it into the hole, a ratchet wheel having means for attaching a wrench and having a double row of teeth spaced by an annular groove, said ratchet wheel rotatably fitting within said hole, movable members positioned within both of said grooves for holding the ratchet wheel in position, a pawl carried by the body and extending toward the shank and a plunger, spring and screw positioned within one end of the bore in the shank for holding the pawl in operative position.

6. A ratchet wrench comprising a one piece body having an integral shank, said body having a hole therethrough and an annular groove adjacent the hole, and the shank having a bore extending through it into the hole, a ratchet wheel having means for attaching a wrench and having a double row of teeth spaced by an annular groove, said ratchet wheel rotatably fitting within said hole, rotatable members positioned within both of said grooves for holding the ratchet wheel in position, a pawl having a plurality of teeth, carried by the body and extending toward the shank and means mounted within the inner part of the bore in the shank for resiliently holding the pawl in operative position.

7. A ratchet wrench comprising a one piece body portion terminating in an integral operating shank, said body having two opposite substantially flat parallel faces and a circular hole extending from one face to

the other, and an annular groove adjacent the hole and centrally disposed between said faces, said shank having a bore of two diameters extending through it into the hole, a ratchet wheel having means for attaching a wrench and having a thickness substantially the same as the distance between said body faces and a diameter slightly less than the diameter of the hole in the body and also having an annular groove centrally arranged for alignment with the groove in the body, rolling members positioned in both grooves for holding the ratchet wheel in position in the hole, a pawl carried by the body and extending toward the shank and means carried in the shank bore of lesser diameter for resiliently holding the pawl in working position against the ratchet wheel.

8. A ratchet wrench comprising a one piece body having an integral shank, said body having a hole therethrough and an annular groove adjacent the hole and the shank having a bore extending through it into the hole, a ratchet wheel having means for attaching a wrench and having a double row of teeth spaced by an annular groove said ratchet wheel rotatably fitting within said hole, rolling members positioned within both of said grooves for holding the ratchet wheel in working position, said body having a slot extending from the hole to the bore in the shank, said slot serving two purposes; first, as a means through which said rolling members may be passed into the grooves following the placing of the ratchet wheel within said hole in the body, second, means for holding a pawl; a pawl positioned in said slot and means positioned within said shank bore adjacent the pawl for resiliently holding the pawl in operative position.

40 In testimony whereof, I affix my signature.
EDWARD B. NOWOSIELSKI.
